UNITED STATES PATENT OFFICE.

THOMAS DAWKINS, OF LONDON, COUNTY OF MIDDLESEX, ENGLAND.

KEY-BOARD FOR REED MUSICAL INSTRUMENTS.

SPECIFICATION forming part of Letters Patent No. 243,861, dated July 5, 1881.

Application filed February 28, 1881. (No model.) Patented in England July 12, 1879.

To all whom it may concern:

Be it known that I, THOMAS DAWKINS, a subject of the Queen of Great Britain, residing at Charter-House street, London, in the county 5 of Middlesex, England, importer and manufacturer of musical instruments, have invented certain new and useful Improvements in Key-Boards for Reed Musical Instruments, (for which I have received Letters Patent in England, No. 2,847, dated 12th July, 1879,) of which the following is a specification.

This invention relates to improvements in the arrangement of the notes and keys of vibrating reed musical instruments acting on 15 the principle of the accordion, concertina, harmonium, and other like musical instruments, which improved instrument I propose to call the "polychord."

The general arrangement of this improved 20 musical instrument consists of a key-board with keys arranged in rows, and divided into sections or groups to form chords. The action consists of levers with springs and pallets similar to those of the harmonium and other 25 like musical instruments. A sounding-board is arranged with reeds or vibrators attached thereto, combined with bellows suitably arranged, and having a suitable lever handle or handles to actuate the same. The form and 30 compass of the instrument may be considerably varied.

In order that my invention may be clearly understood and readily carried into practice, I will proceed to describe the drawings hereto 35 annexed, which show several views of a musical instrument arranged and constructed in accordance with my improvements.

Figure 1 is a plan, Fig. 2 a longitudinal section, Fig. 3 an end view, and Fig. 4 a trans- 40 verse section, of the same.

A A in all the figures is the key-board, arranged with keys *a a' b b' c c'* in parallel lines,

divided into groups 1 2 3 4 5, (or it may be more or less in number,) which groups contain full chords in the "tonic," "dominant," and "sub-dominant" of each major and minor key, the major being placed at the side of its relative minor. In each of the groups 1 2 3 4 5, (shown in Fig. 1,) *a* and *a'* represent, respectively, the keys arranged to correspond with the notes of tonic major and relative minor chords in one key; *b* and *b'* the same for the dominant chords in the same key, and *c c'* the same for the sub-dominant. The longitudinal and transverse sections, Figs. 2 and 4, show the arrangement and construction of the notes, keys, and bellows, *d* being the lever-handle by which the bellows are actuated, and *d'* another lever-handle used for the same purpose.

A set of keys may be also arranged chromatically in the same order as that of the piano-forte, as represented by Figs. 5 and 6 of the drawings, for the purpose of playing symphonies or airs on the instrument when desired.

Having thus described my invention, and the manner of carrying the same into practice, I would remark that I do not claim any of the parts separately, which are well known and in common use; but

What I claim is—

A musical reed instrument in which the keys are arranged upon the key-board in parallel lines divided into sections, each section having the keys grouped or arranged to correspond with the notes of the full chords of the tonic, dominant, and sub-dominant of a major key and its relative minor, as set forth.

THOMAS DAWKINS.
